HENRY G. PEARSON, OF NEW YORK, N. Y.

Letters Patent No. 73,379, dated January 14, 1868.

MECHANICAL TOY.

The Schedule referred to in these Letters Patent and making part of the same.

TO ALL WHOM IT MAY CONCERN:

Be it known that I, HENRY G. PEARSON, of the city, county, and State of New York, have invented certain Improvements in Mechanical Toys; and I do hereby declare that the following, taken in connection with the drawings which accompany and form part of this specification, is a description of my invention sufficient to enable those skilled in the art to practise it.

Most mechanical toys are either complicated or costly. When elaborate machinery resembling clock-work is employed to propel them, or to give motions to the movable parts, it is easily deranged, and then the toy loses its principal attraction, and is apt to be laid aside as useless, the expense of repairing being frequently greater than the original cost.

A simple and attractive toy, in which, by the mere rolling of a hoop or wheel, at the centre of which an image or other object is suspended, and thus given a sort of swinging motion, has been heretofore made, and has proven very popular.

My invention has for its object an improvement upon this class of toys; and it consists in giving to the limbs of the toy-animals suspended in the ring, or to the members or parts of any other object so suspended, determined movements, or positive movements by mechanism of the simplest kind, not liable to damage or derangement, the motion-giving mechanism being brought into action by the mere rolling of the hoop or wheel.

Figure 1 of the drawings affords an illustration of one of the almost endless forms in which my invention may be embodied.

Figure 2 represents the same when viewed from the side, and exhibits, also, my improved construction of the hoop.

Figure 3 represents, detached, a view of the axis upon which the central image is suspended, and which also is bent so as to form the cranks, which give the desired motions to the moving parts.

Figure 4 is a detached view of the crank, showing its connection with a link, which, through it, gives motion to the limbs; and also a modification of such connection of the crank with the limb, the same being by means of a slot in a rigid arm, projecting from the limb.

Instead of employing for the hoop or wheel a sheet of tin, as is customary, and then, for the sake of giving the requisite strength, binding it with a strong edging of wire, I form my ring with the wire merely, dispensing entirely with the sheet metal. The advantages of this construction are, not only greater rapidity and cheapness in the manufacture, but also the more important one of affording a clear and uninterrupted view of the object from all directions, unobstructed by the interposition of the broad wheel between the central object and the eye of the observer. These wire rings I prefer to unite into a skeleton frame, as shown in fig. 2, composed merely of two or more rings, A, united by cross-ties, B, of wire, which may be soldered or otherwise secured thereto. In a wheel thus constructed, as shown at A in the figures, I attach to the opposite sides of each wire ring a cross-wire, C, bisecting the same, these two cross-wires affording a support for another wire, D, at the centre or axis of the ring. Instead, however, of making this wire, D, in a straight line, as heretofore, merely as a point of suspension for a swinging body, I form it as shown at fig. 3, bent into the form of cranks, two such cranks being sufficient to impart the motions needed for the movements of the legs of a quadruped, although when more or different motions are required, more cranks, or cranks arranged in different relations to each other, will of course be demanded. The parts marked E and F must of course be in line with each other, and should be in line with the centre of the rings, unless, for the purpose of producing irregular or grotesque movements, it be desired to locate them elsewhere. To each crank are connected two links or wires, G, whose other ends are connected to the upper and shorter arms of the legs, which are hung as loose levers upon pivots secured to the body of the image, as shown in the drawings. In the construction, shown in fig. 1, one crank is connected to the two right legs, and the other to the two left legs, the legs being weighted sufficiently to insure their always hanging down.

The effect and operation of a toy so constructed, when the wheel is rolled about, is as follows: Each revolution of the wheel causes a revolution of the cranks which are secured to it, and inasmuch as the toy is so weighted as not to revolve coincidently with them, the cranks must of necessity give motion to the links, which impart it to the legs. By this means the legs derive a motion closely resembling that of the living animal, the

feet upon either side approaching each other, whilst those upon the other side recede from each other, and *vice versa*. When, however, it is needed to exhibit the movements of a leaping quadruped, the fore feet may be made to move together in one direction, whilst the hind feet move together in the opposite direction, by merely changing the connections of the links with the legs, so that one crank shall be connected with both fore legs, and the other with both hind legs.

It is obvious that by variations in the length or number of the cranks, or in their points of connection with the links, or in the length of the links, or in their points of connections with the objects or parts of the body to be moved, or in the fulcra of the limbs or other part of the body, which is pivoted for the purpose of being changed in its position, or by the multiplication of connecting-links, all in any well-known manner familiar to mechanics, the range of motions attainable by my invention is almost without limit, the rolling of the wheel being the motive-power, and the consequent revolution of the crank communicating whatever resultant motions fancy or taste may demand, dependent merely upon the form and character of the intermediate links and connections. Instead of links like G, a single piece of wire, bent at each end into the form of a hook or eye, passing through and connecting with a hole in the part to which it is desired to give motion, may be used. Instead of such movable links as above described, the limb or other object may have a rigid slotted arm projecting from it, somewhat as shown at H, in fig. 4, the crank passing through this slot. All the cranks, connections, and pivots may be concealed and protected within the body of the animal or other object.

Figure 5 represents a modification of my invention, in which the wheel A is identical in structure with that above described, except that, instead of two bisecting wires, a single rod or wire, K, rigidly secured at one end to one of the cross-braces I, and free at its other end, which terminates at or near the centre of the ring, forms the only support for the image or object to be put in motion. The revolution of the wheel must of course carry this wire or rod with it, and also whatever object is secured to its inner end. All, therefore, revolve together. To give the parts to which additional motions are to be imparted, movements resembling those which appertain to them, it is simply necessary that they be loosely jointed about at the same relative points as in the real object or body, and that there be some limit or check to prevent these parts assuming positions which, in the real object, are unnatural or impossible. When such checks are not employed, very ludicrous and grotesque movements and attitudes are produced. In the image illustrated in fig. 5, I have shown the arms, thighs, and knees jointed, the joint in this case being a wire loop, answering at the same time for a pivot and a detent or arrester of motion, the letter *a* designating the pivot, *b* the detent, and *c* such ears, nicks, or faces as serve to arrest the farther motion in one direction of the movable parts the moment they come in contact with *b*. Instead of using such loop, the limbs may swing on a pivot, and be arrested in their motions by another pin or projection, suitably located. The revolution of the wheel, carrying with it such a figure as is represented in fig. 5, causes it to mimic with surprising accuracy the graceful movements of a skillful athlete. By having the wire, K, sufficiently slender to permit it to get a slight vibratory motion, other effects are produced, which in many cases enhance the value and attractiveness of the toy.

It is evident that when constructed substantially as shown in fig. 1, if the axis be projected a short distance through both sides of the body of the image, so as to form bearings, the wheel may then be suspended upon supports, or in a handle, or by cords, and instead of rolling upon a plane, as hereinbefore stated, it may then be revolved on the points of suspension without rolling away from the person. The positive motions of the image in such case remain the same, but the opportunities for inspecting them are better.

1. I claim a mechanical toy, the positive motions of whose parts are derived from a crank or cranks on the axis of a rolling or revolving hoop.
2. I claim the combination, with such a crank or cranks, of a system or systems of connecting-links, substantially as shown and described.
3. I claim, in combination, a revolving hoop, carrying a suspended image or toy which does not revolve, but whose members are given positive and determined movements, substantially as described.
4. I claim the combination, with the rolling hoop of a mechanical toy, of a radial arm, projecting from the hoop towards its centre; as and for the purpose set forth.
5. I claim the combination, with such a hoop and radial arm, of a jointed image.
